UNITED STATES PATENT OFFICE.

CARL S. NORDEN, OF HAVERHILL, MASSACHUSETTS, ASSIGNOR TO UNITED SHOE MACHINERY CORPORATION, OF PATERSON, NEW JERSEY, A CORPORATION OF NEW JERSEY.

HEEL-SEAT-FITTING MACHINE.

Application filed July 19, 1920. Serial No. 397,243.

This invention relates to the manufacture of shoes and more particularly to heel seat fitting machines.

In the manufacture of such shoes as are to be provided with wooden heels it is necessary before the heel is attached to trim away a part of the heel seat portion of the sole of the shoe in order to conform the sole to the concave heel seat portion of the wooden heel. This is known as heel seat fitting. Different individual wooden heels, even those of the same lot and intended to be of the same size, may vary considerably in size and shape. It is desirable, accordingly, in order to produce high grade work on such shoes, to fit each wooden heel individually to the particular shoe to which it is to be attached. When, as has heretofore been the general practice, this operation is performed by hand the operative ordinarily applies the wooden heel to the heel seat portion of the sole of the shoe to which it is to be attached and, using the heel itself as a guide, makes a mark or a pair of marks upon the sole of the shoe to indicate the exact position which the breast of the heel occupies. Then he removes the heel and trims away a part of the heel seat portion of the sole of the shoe with a knife, forming a more or less U-shaped bevel extending from the position of one heel breast corner to that of the other around the heel seat portion of the sole, and provided with a pair of shoulders forming an abutment against which the breast corners of the heel are placed when the heel is attached.

In view of the foregoing, it is an object of this invention to provide an improved machine which, without sacrificing the advantages of any of the machines heretofore devised, will further facilitate the performance of heel-seat-fitting operations, in order that such operations may be performed more accurately, more quickly and otherwise more economically and satisfactorily than heretofore.

In the attainment of this object, features of the invention reside in means for supporting the periphery of the heel seat portion of the sole of a shoe while leaving the center of the sole unsupported, together with means for pressing against the center of the heel seat portion to distort the heel seat to render it concave for the action of heel seat

trimming knives. In accordance with this and other features, the illustrated supporting means comprises a plurality of thin-edged adjustable plates constructed and arranged to conform substantially to the sides and the rear of a shoe and adapted to enter the rand crease of the shoe, to protect the upper from the knives and at the same time to support the periphery of the sole while a presser member is provided for depressing the center of the heel seat portion of the sole and offsetting its periphery upwardly. This allows the knives to form a U-shaped bevel around the heel seat portion by cutting inwardly from the edge toward the tread surface while moving in a path substantially parallel to the plane of the tread surface of the sole, thus providing a simple but effective organization.

Another feature of the invention consists in the provision of a series of knives operated automatically in sequence to trim the periphery of the heel seat portion of the sole of a shoe. The illustrated knives are arranged to make overlapping cuts, a knife located at the back of the shoe being preferably operated first and then opposite knives at the sides of the shoe being moved inwardly in pairs successively to form a bevel continuous throughout the range of operation of the knives.

Another object of this invention is to provide improved means for obtaining the desired shoulder formation at the heel breast line, which will correspond to the shape of the breast of the heel and which will not tend to stretch or otherwise distort the sole of the shoe. With this object in view I provide a support for a shoe and cutting means movable inwardly across the shoe bottom, the cutting means preferably being constructed and arranged simultaneously to bevel the adjacent portion of the sole. In the illustrated embodiment of my invention, two shoulder-cutters are provided, movable toward one another, to form shoulders on opposite sides of the sole.

To provide for the proper formation of the shoulders, and at the same time to subdivide the chips cut from the periphery of the sole, certain of the knives, including the shoulder-cutters, are provided with angularly arranged cutting edges, and in order further to facilitate the formation of the de-

sired shoulder cuts, provision is made for varying the position of the angular cutting edges of the shoulder-cutters longitudinally of the sole and angularly with respect to the sole during their transverse cutting action, to form a curved shoulder.

In accordance with another feature of the invention, the illustrated rand crease plates at the sides of the shoe are provided with 10 indicating means comprising marks arranged in predetermined relation to the cutting means to facilitate the correct positioning of the shoe in the machine. In 15 using the illustrated machine, it is contemplated that, advantageously, the operative will first mark the position which the heel is to occupy upon the sole of the shoe just as in performing the operation by hand, and then position the shoe in the machine 20 with the mark or marks thus made in alignment with the indicating marks of the machine, whereby the correct positioning of the shoe in the machine is assured and the extent of the trimming may be correctly regulated. The novel shoe supporting means of 25 the machine, which are adjustable for length and breadth, permit such a positioning of shoes of various sizes.

Preferably, and as illustrated, indicating 30 marks disposed in angular relation to one another are provided arranged to be registered respectively with corresponding marks upon soles of shoes designed to have various types of heels.

Still further to adapt the machine to fitting the heel seats of shoes designed to have heels differing in the curvature of the heel breast, the illustrated machine is provided with a pair of opposed knife-guides 40 of one curvature, for example designed to conform to the curvature of a heel having a straight or substantially straight heel breast, and a second pair of opposed knife-guides having a curvature different from the curvature of the guides of the first pair, the pairs of guides being constructed and arranged 45 to be used alternatively to guide sole-trimming knives transversely of the shoe sole at the heel breast line.

With these and other objects and features in view the invention will now be described in connection with the illustrative machine of the accompanying drawings, and pointed out in the appended claims.

In the drawings,

Fig. 1 is a perspective view of the illustrative machine with certain portions broken away more clearly to show the construction thereof;

Fig. 2 is a perspective view on a larger scale of a portion of the machine, showing the cutters and their relation to a shoe which has been operated upon and to which a heel requiring a straight breast cut is to be attached;

Fig. 3 is a plan view showing the relation of the cutters to a shoe, to which a heel requiring a curved breast cut is to be attached, before the performing of the heel seat fitting operation and showing also the relation of the indicating marks of the machine to an indicating mark on the sole of the shoe;

Fig. 4 is a longitudinal section through the heel portion of a shoe showing the relation of the shoe to the jack and to one of the cutters; and

Fig. 5 is a perspective view of the heel seat portion of a shoe upon which the heel seat fitting operation has been performed by the machine of the present invention.

The machine, as illustrated, is provided with a base 10 having formed therein a slideway 12 in which is movably mounted a jack 14 provided with a concave upper portion 16. At the rear of the machine there is provided a pair of standards 18 to the upper portion of which is fulcrumed a lever 20 arranged to be rocked through a treadle 22 and carrying at its forward end a rod 24 to which is pivoted a convex presser member or holdown 26. It will be evident that pressure applied to the heel seat portion of the sole of a shoe supported upon the jack will result in somewhat concaving the heel seat portion of the shoe, as indicated in Fig. 4, due to the co-operating concave and convex surfaces of the jack and the presser member respectively and their relation to rand crease entering plates 32, 33 and 34 to be 95 described. This depresses the central part of the heel seat at the same time offsetting the periphery upwardly relatively to the central part and thus facilitates the removal of a U-shaped portion from the periphery 100 of the tread face of the sole by knives movable inwardly substantially in the plane of the tread face.

Supported by the base 10 of the machine is a U-shaped table 30 by which is carried a 110 series of jaws or crease plates 32, 33, 34, having thin edge parts shaped to the sides and back of a shoe and arranged to enter the rand crease of a shoe supported upon the jack 14. Jaws 32 and 34 are provided with 115 indicating marks 200 and 300 disposed in angular relation to each other, as will be more fully explained hereinafter. In the illustrated machine these crease plates are independently adjustable being connected to the 120 table 30 by pins 36 sliding in bearings 38 carried by the table 30 and normally resiliently held in the position shown in Fig. 1 by compression springs 40. Thus the rand crease entering jaws may take different positions in accordance with the size and shape of the shoe placed in the machine, and are so located that, having entered the rand crease to engage the inseam, they will support the sole and protect the upper of the 130

shoe during the heel seat fitting operation. The table 30 of the machine is also provided with a series of undercut, straight grooves 42 in which are slidably mounted carriers 44 for the cutters or knives 46. In the illustrated machine these carriers or knives are seven in number, there being a single carrier and knife at the rear and three carriers and knives upon each side of the machine. The knives are 10 constructed and arranged to make overlapping cuts and certain of these knives are provided with angular extensions 47 to their cutting edges, for the purpose of cutting the strip of material removed from the tread 15 surface of the sole into a number of chips to facilitate the operation of the knives, and other extensions are provided at the forward edges of the foremost knives for the purpose of forming a pair of shoulders at the forward 20 extremities of the beveled portion against which the breast corners of the heel may be positioned.

As indicated in Figs. 1 and 2, the table 30 of the machine is provided with still another pair of grooves 48, curved instead of straight, and intended to be used alternatively with the foremost grooves 42 to support carriers and knives arranged to have the position of their cutting edges varied 30 longitudinally of the sole and angularly with respect to the longitudinal axis of the sole so as to travel upon an arcuate path, these knives being used, as shown in Fig. 3, when it is desired to perform the heel seat 35 fitting operation upon a shoe which is to be fitted with a heel requiring a curved breast cut while the foremost carriers and knives, traveling in a straight path, are to be used when the heel seat fitting operation is to be 40 performed upon a shoe having a heel requiring a straight breast cut. The pair of knives and carriers not to be used are, of course, removed from the machine.

Suitable mechanism is provided for operating the knives or cutters. As shown in Fig. 4, the rearmost carrier is provided with a pair of downwardly extending lugs 50 arranged to receive the end of a bell crank lever 52 rigidly mounted upon a shaft 54 and rocked in the operation of the machine by means of a cam 56 keyed to a shaft 58. Loose upon shaft 58 is a pulley 60 driven from any suitable source of power and arranged to be connected to the shaft 58 by 50 any desired form of one revolution clutch, as indicated diagrammatically at 62. The shaft 58 is connected by suitable gearing 68 with a pair of shafts 66, one upon each side of the machine, and the carriers and knives 60 at the sides of the machine are driven from these shafts in a manner similar to that by which the rearmost knife and carrier are operated from shaft 58. A suitable spring 70 is provided, anchored at one end to the 65 frame of the machine and at the other end

to the bell crank lever 52 and operating to withdraw the rearmost knife at the conclusion of its cut. Springs 72 are provided to perform the same function with respect to the other knives. 70

As indicated in Figs. 1 and 2, the knives 46 carried by the foremost carriers 44 are pivoted thereto as at 74 about an axis generally parallel to the edge of the sole for movement in a plane substantially parallel to the tread face of the sole and are provided with rearward extensions 76 normally held in the position indicated in Fig. 1 by compression springs 78. Each of these knives is also provided with an upwardly extending finger 80 to which is connected, as by a suitable loose joint 82, the end of a rod 84. This rod is longitudinally movable with respect to a sleeve 86 suitably supported by the table 30 as by a rod 88, on which is slidably mounted a sleeve 87 to which sleeve 86 is pivoted. The rod 84 is illustrated as screw-threaded at its outer end and carries a nut 188 adjustable along the screw-threaded portion. This nut is carried in such position that after the knife has commenced to bevel the heel seat portion of the sole of the shoe the nut will contact with the sleeve 86 and thus the cutting edge of the knife will be rocked upwardly, this action assisting in the cutting of the sole in the desired manner to form at the heel breast line a shoulder progressively diminishing in height inwardly from the edge of the sole. By the adjustment of the nut the extent or form of the bevel also may thus be varied. 95

When the heel seat fitting operation is to be performed upon a shoe to which a heel requiring a curved breast cut is to be attached, the foremost knives and carriers of Fig. 1 are replaced by the knives and carriers which travel in a curved path. The sleeves 86 may then be adjusted along the rods 88 so that they will be in the proper position to engage the fingers 80 of those knives, the operation of the machine under these circumstances being facilitated by the pivoting of sleeves 86 to sleeves 87 and cramping being thereby avoided. 105

The knives other than the foremost pair are illustrated as being of a curved formation and adjustably connected as by screw and slot connections with their carriers, the latter also being curved. The curvature of these knives and carriers, as well as of the guides in which they slide, is such that as the knives enter the leather of the sole of the shoe their paths, instead of being straight lines, are all somewhat curved upwardly. By thus causing the cutting edges of the knife to travel in a curved path, which is, however, through its relatively short movement, in a direction substantially parallel to the undeformed portion of the tread face of the sole, the cut is such that 110 120 125 130

the desired bevel may be formed about the heel seat portion of the shoe without an excessive deformation of the sole by the concave surface 16 of the jack and the convex surface of the presser member 26.

If desired, co-operating indicators and scales may be carried by the knives and their carriers. This is illustrated in Figs. 1 and 4 in connection with the rearmost knife, and 10 serves as an aid in adjusting the knife in accordance with the size of shoe to be operated upon.

In using this machine to perform the heel seat fitting operation, the operative first 15 places the heel in the position which it should occupy upon the sole of the shoe and makes a mark in conformity with the breast of the heel, as indicated at 100 in Fig. 3. He then places the shoe upon the jack, the 20 crease plates 32, 33, 34, entering the rand crease of the shoe, and the mark 100 being placed in alinement with marks 200 or 300 upon the jaws 32 and 34 according as the heel is a heel requiring a straight or a curved 25 breast cut, such placing of the work being permitted by reason of the adjustable back plate and the independently adjustable side plates. Then by depressing the treadle 20 the presser member or holdown 26 is 30 brought down upon the heel seat portion of the sole of the shoe thereby slightly distorting the periphery of the heel seat. With the shoe in this condition, the clutch is 35 tripped and the knives are operated in sequence to perform the cutting operation. In the illustrative machine, the timing of the knife operating cams is such that the rearmost knife is operated first, then the two knives of the pair adjacent thereto, then the 40 intermediate knives and then the forward knives. At the same time that the forward knives cut their portions of the bevel they also, by reason of the angular formation of their cutting edges, are arranged to form 45 the shoulders at the forward portion of the heel seat and against which the breast corners of the heel are to be abutted.

While the invention has been shown and described as embodied in a particular machine it should be understood that this is 50 for purposes of illustration only, and without intent of limitation thereby.

Having described my invention, what I 55 claim as new and desire to secure by Letters Patent of the United States is:

1. A heel seat fitting machine comprising, in combination, a plurality of supports to enter the rand crease of a shoe, one of said supports at one side of the shoe being provided with an indicating mark to register with a mark on a shoe held thereby, and means to remove the waste stock about the heel seat of a shoe to an extent previously indicated by said mark.

2. A machine of the character described

having a plurality of members constructed and arranged to enter the rand crease of a shoe, said members being provided with a plurality of indicating marks disposed in angular relation to one another, one of 70 which is arranged to register with a corresponding mark upon the sole of a shoe having one type of heel to facilitate the positioning of the shoe in the machine, and another of said marks being arranged to register with a corresponding mark upon the sole of a shoe designed to have another type of heel.

3. A heel seat fitting machine having, in combination, shoe holding means constructed and arranged to enter the rand crease of a shoe, a presser member, means for forcing the presser member against the heel seat portion of the sole of the shoe and for holding it stationary with respect thereto, and means for beveling the heel seat portion of the sole of the shoe.

4. A heel seat fitting machine having, in combination, a jack for supporting a shoe, a presser member co-operating therewith to concave the heel seat portion of the sole of the shoe, a series of knives movable towards the shoe to bevel the periphery of the heel seat portion of the sole thereof, and mechanism to move said knives in sequence towards the sole of the shoe so as to bevel in sequence different portions of the periphery of the heel seat portion thereof, said jaws being provided with means arranged to co-operate with corresponding marks upon the sole of the shoe correctly to position the shoe with respect to the knives.

5. A heel seat fitting machine having, in combination, a jack for supporting a shoe and a knife having a blade provided with an angular cutting edge, and means constructed and arranged relatively to move the knife and a shoe supported by the jack to cause the knife to operate from the edge of the sole inwardly to bevel a portion of the heel seat of the outsole of the shoe and at the same time to cut a shoulder at the termination of the bevel and against which shoulder the forward portion of the wood heel may be placed to position the heel with respect to the shoe.

6. A heel seat fitting machine having, in combination, a jack for supporting a shoe and a plurality of knives arranged to form a U-shaped bevel around the heel seat portion of the sole of a shoe, certain of said knives being provided with angular blades to form a pair of shoulders at the opposite sides of the heel seat portion of the sole and against which the forward portion of a wood heel may be placed to position the heel with respect to the shoe.

7. A heel seat fitting machine having, in combination, means for supporting a shoe, a knife having a blade provided with an

- angular cutting edge, and means to operate the knife from the side of the shoe inwardly to bevel a portion of the heel seat of the outsole of the shoe.
5. 8. A heel seat fitting machine having, in combination, a support for a shoe, a plurality of knives, and mechanism constructed and arranged to operate said knives in directions generally parallel to the sole of the shoe.
10. 9. A heel seat fitting machine having, in combination, means for supporting a shoe, means to concave the heel seat portion of the sole of the shoe, a series of knives, and mechanism arranged to operate said knives in sequence to form a U-shaped cut around the heel seat portion of the sole of the shoe.
15. 10. A heel seat fitting machine having, in combination, a jack for supporting a shoe, a presser member arranged to co-operate with the jack to concave the heel seat portion of the shoe, a series of knives, and mechanism for operating said knives in sequence to form a U-shaped bevel around the heel seat portion of the sole of the shoe.
20. 11. A heel seat fitting machine having, in combination, means to support a shoe, a knife, and means to cause the cutting edge of said knife to travel from the edge inwardly in a curved path transversely of the sole of the shoe to trim a portion of the periphery of the heel seat portion of the sole of the shoe.
25. 12. A heel seat fitting machine having, in combination, means to support a shoe, a knife mounted for pivotal and linear movement, and mechanism to cause said knife to bevel a portion of the heel seat portion of the sole of the shoe constructed and arranged to move said knife linearly towards the shoe and to cause said knife to swing about its pivot towards the tread surface of the sole thereof.
30. 13. A heel seat fitting machine having, in combination, a jack for supporting a shoe, a series of knives bodily movable in a direction to co-operate in forming a bevelled surface about the periphery of the heel seat portion of a shoe supported upon the jack, and means so to move said knives.
35. 14. A trimming machine comprising, in combination, means for supporting the periphery of a piece of stock but leaving the center unsupported, a member to engage the unsupported center, and bulge it out through said supporting means and then hold it clamped, and cutting means operating on the stock while it is so clamped and constructed and arranged to bevel the periphery of the stock.
40. 15. A heel seat fitting machine comprising, in combination, co-operating members to clamp the sole of a shoe between them with

the heel seat portion distorted, and means to trim the heel seat while it is held thereby.

16. A trimming machine comprising, in combination, a knife, and means to move the knife in a curved path transversely inwardly from the edge of a piece of stock to form a bevel thereon corresponding to the curve of the path.

17. A heel seat fitting machine comprising, in combination, a support for a shoe, a slide movable in a plane approximately parallel to the sole of the shoe, and cutting means actuated by the slide to form angularly related cuts to form a shoulder at the heel-breast line and to remove waste stock rearwardly thereof.

18. A trimming machine comprising, in combination, trimming knives arranged in a series and constructed and arranged to co-operate to remove adjacent chips of waste from a piece of stock to make a continuous cut extending along the range of operation of said knives, and mechanism automatically to actuate said knives successively.

19. A machine for operating on shoes having, in combination, an instrumentality to operate on a shoe, and a support for a shoe operated on thereby comprising a plurality of members to engage in the crease between the upper and sole of the shoe and a pair of spring-pressed plungers to carry each member and allow it to accommodate itself to the different shapes of different shoes.

20. A sole trimming machine comprising, in combination, a pair of knives having angular cutting edges, and means to move them toward one another in directions generally transverse to the opposite edges of a sole at the heel breast line.

21. In a sole-trimming machine, in combination, a pair of opposed knife guides, and a second pair of opposed knife guides having a curvature different from the curvature of the guides of the first pair, said pairs of guides being constructed and arranged to be used alternatively to guide sole-trimming knives transversely of a shoe sole at the heel breast line so that the curvature of the cuts at the breast line of a sole may conform to the curvature of the heel breast of a given heel.

22. A heel seat fitting machine comprising, in combination, knives movable inwardly from the edges of the sole to make cuts at the heel breast line, and means co-operating therewith to remove the waste stock about the heel seat of the sole rearwardly of the cuts made thereby.

23. A trimming machine comprising, in combination, a support for a shoe, a knife movable in a direction parallel to the heel breast line and parallel to the plane of the sole, and a cam-operated lever to move the knife to make a cut from the edge of the sole inwardly.

24. A heel seat fitting machine comprising, in combination, means to clamp the heel end of a shoe, knives moving inward from the edges of the sole of a shoe clamped thereby 5 to make cuts corresponding in shape to the breast of a heel, and means co-operating therewith to remove the waste stock about the heel seat of the sole rearwardly of said cuts.
- 10 25. A heel-seat fitting machine comprising, in combination, a support for a shoe, a knife movable across the sole of the shoe from one edge to form a shoulder to engage the breast of a wood heel, and means for removing waste stock rearwardly of the shoulder 15 to form a convex surface to receive the seat of the heel.
- 20 26. A heel-seat fitting machine comprising, in combination, means for positioning a shoe, a cutter, and means to traverse it across the shoe from one edge of the sole in a direction substantially parallel to the shoe bottom to form a shoulder to engage the breast of a wood heel, and stock-removing 25 means to form a convex surface on the sole rearwardly of the shoulder to receive the seat surface of the heel.
- 30 27. A heel-seat fitting machine comprising, in combination, a support for a shoe, a heel-breast knife movable inwardly from the edge of the sole of the shoe, and means to rock the knife about an axis generally parallel to the edge of the sole to form at the heel-breast line a shoulder progressively 35 diminishing in height inwardly from the edge of the sole.
- 40 28. A machine for operating on shoes to which the soles have been attached having, in combination, an instrumentality to operate upon a shoe, and a support for a shoe to be operated upon thereby comprising laterally disposed thin-edged crease plates having a curved contour constructed and arranged to enter into the crease to an extent 45 determined by the construction of the shoe bottom and to engage said shoe in the crease between the upper and the sole of the shoe adjacent to the heel seat and means for guiding said plates for movement in a direction 50 transversely of the sole.
- 55 29. A machine for operating on shoes having, in combination, an instrumentality to operate upon a shoe, and a support for a shoe to be operated upon thereby comprising a frame and a plurality of members constructed and arranged with thin edges to enter into the crease and slidably mounted in said frame to engage the shoe and enter a substantial distance the crease between the 60 upper and the sole, laterally of the shoe and at the rear of the shoe, respectively, said members being relatively movable in said frame to allow said support to be accommodated to the different shapes of different 65 shoes.
30. A machine for operating on shoes having, in combination, an instrumentality to operate upon a shoe, and a support for a shoe to be operated upon thereby comprising a plurality of crease plates with thin edges 70 formed to enter the rand crease and to engage the inseam between the upper and sole of the shoe and constructed and arranged for adjustment both for width and length, whereby said support may accommodate it- 75 self to the different shapes of different shoes.
31. A machine for operating on shoes having, in combination, an instrumentality to operate upon a shoe, and a support for a shoe to be operated upon thereby comprising a plurality of relatively movable crease plates having thin edge parts formed to conform substantially to the sides and back of a shoe at the heel region, and to enter between and to engage the extension of the 80 outsole and the upper of a shoe to which the sole has been permanently attached, said crease plates including an independently adjustable member to engage the shoe at the rear.
32. A heel seat fitting machine comprising, in combination, a plurality of supports to enter the rand crease of a shoe, one of said supports being provided with an indicating mark to register with a mark on a shoe held 85 thereby, and cutting means a part of which acts along a path coinciding with said mark to remove the waste stock about the heel seat of the shoe to an extent previously indicated by said mark.
33. A heel seat fitting machine having, in combination, a plurality of supports to enter the rand crease of a shoe comprising a crease plate constructed and arranged to engage the shoe at the rear and crease plates 90 for the sides of the shoe, one of which side crease plates is provided with an indicating mark to register with a mark on a shoe engaged thereby, whereby the shoe may be positioned and supported in the machine 95 with the mark on the shoe in register with the mark on the side crease plate, and means to remove the waste stock about the heel seat of the shoe to an extent indicated by said mark.
34. A heel seat fitting machine for operating upon the sole of a shoe having, in combination, means for supporting the shoe, cutting means disposed adjacent to the edge of the sole and movable inwardly to bevel a 100 portion of the tread face at the rear of said sole to provide a substantially convex seat for a heel which is to be attached to the shoe, and means for controlling the operation of said cutting means to vary the convexity of the heel seat.
35. A heel seat fitting machine for operating upon the sole of a shoe having, in combination, means for supporting the shoe, and means moving inwardly simultaneously from 105

opposite sides of the sole for trimming a portion of the bottom face at the rear of said sole to assist in providing a seat for a heel which is to be attached to the shoe and for forming a shoulder adjacent to said trimmed portion to fit the breast of the heel.

36. A heel seat fitting machine for operating upon the sole of a shoe having, in combination, means for supporting the shoe, a knife having angularly disposed cutting edges, means for moving said knife from a position adjacent to a lateral edge of the sole transversely of the sole to cause one of said cutting edges to bevel a portion of the tread face of the sole, and means for varying the position of said cutting edges longitudinally of the sole and angularly with respect to the longitudinal axis of the sole during said transverse cutting stroke so that the other of said cutting edges will form a curved shoulder adjacent to said beveled portion.

37. A heel seat fitting machine for operating upon the sole of a shoe having, in combination, a cutter for forming a shoulder at the breast line of the sole, said cutter being disposed outside the lateral edge of the sole, means for causing relative movement of the cutter and the sole to transfer the point of operation of the cutter toward the center of the sole, and guiding means for controlling said relative movement in a manner to cause said shoulder on the sole to be curved in the plane of the sole.

38. A heel seat fitting machine for operating upon the sole of a shoe having, in combination, a cutter for forming a shoulder at the breast line of the sole, said cutter being disposed outside the lateral edge of the sole, means for causing relative movement of the cutter and the sole to transfer the point of operation of the cutter toward the center of the sole, and guiding means for controlling said relative movement in a manner to cause said shoulder on the sole to be curved in the plane of the sole and the transverse cut to decrease in depth from the lateral edge of the sole inwardly toward the central portion thereof.

39. A heel seat fitting machine having, in combination, means constructed and arranged to support the periphery of the sole of a shoe adjacent to the heel seat portion thereof, a presser member co-operating therewith to concave the heel seat portion of the sole and for holding it stationary with respect thereto, a series of knives movable towards the shoe to bevel the periphery of the heel seat portion of the sole, and mechanism to move said knives in sequence towards the sole of the shoe so as to bevel in sequence different portions of said periphery.

40. A heel seat fitting machine having,

in combination, means for supporting a shoe, a series of knives bodily movable in a direction to co-operate in forming a beveled surface about the periphery of the heel seat portion of a shoe supported by said means, certain of said knives being arranged to make overlapping cuts, and means so to move said knives.

41. A heel seat fitting machine having, in combination, a support for a shoe, a plurality of knives, certain of said knives being arranged to make cuts overlapping the cuts of other knives and being provided with angularly arranged cutting edges to divide the chips formed by the cuts of adjacent knives, and mechanism constructed and arranged to operate said knives in a direction generally parallel with the sole of the shoe to remove waste stock around the heel seat portion of the sole to form a convex surface to fit the seat of a wood heel.

42. A heel seat fitting machine having, in combination, means for supporting a shoe, a series of knives comprising a knife located at the back of the shoe and a plurality of pairs of knives adjacent to one another located along the sides of the shoe, said knives being bodily movable inwardly from the edge of the sole toward the tread face thereof to co-operate in forming a beveled surface about the periphery of the heel seat portion of a shoe supported in said machine, and means so to move said knives as to actuate first the back knife and then the adjacent pairs of opposite knives successively.

43. A machine for operating on shoes having, in combination, an instrumentality to operate upon a shoe, a plurality of relatively movable thin-edged crease plates adapted to enter the crease between the extension of the outsole and the upper of a shoe, and a hold-down device bearing upon the heel seat portion of the tread surface of the sole adjacent to said crease plates to co-operate with the crease plates in supporting a shoe in the machine.

44. A machine for operating upon shoes having, in combination, an instrumentality to operate upon a shoe, a plurality of thin-edged relatively movable crease plates arranged to engage the shoe between the upper and the sole thereof, and a member movable against the heel seat portion of the sole adjacent to the crease plates arranged to distort the heel seat of the sole to raise the peripheral portion thereof above the central portion.

45. A machine for operating upon shoes having, in combination, an instrumentality to operate upon a shoe, a plurality of thin-edged relatively movable crease plates arranged to engage the shoe between the upper and the sole thereof, a hold-down member movable against the outside surface of the

- heel seat portion of the sole adjacent to the crease plates, and a support adapted to be positioned within the shoe substantially in alignment with said holdown.
5. 46. A heel seat fitting machine having, in combination, shoe-holding means constructed and arranged to enter the rand crease of a shoe, a holdown co-operating with said shoe-holding means and arranged to bear 10 against the tread surface of the sole intermediate between said crease plates, and a trimming knife operable from the peripheral edge of the sole inwardly substantially at the heel breast line thereby to bevel a portion 15 of the heel seat of the sole.
47. A heel seat fitting machine having, in combination, means for distorting the heel seat of the sole of a shoe to raise the peripheral portion above the central portion of the 20 heel seat, and a trimming knife operable from the periphery of the sole inwardly through the distorted edge substantially at the heel breast line to make a beveling cut in the heel seat of the sole.
25. 48. A machine for preparing the rear end of the sole of a shoe for the attachment of a heel comprising shoe-supporting means, and a cutter having a cutting edge movable in a path lying in a surface substantially normal to the plane of the sole of the shoe, said cutter being movable inwardly from the edge of the sole toward the center thereof 30 constructed and arranged to form a shoulder in said sole adjacent to the heel-breast line for co-operation with the complementary part of a heel.
49. A sole-trimming machine comprising, in combination, a pair of knives having cutting edges extending heightwise of the sole 40 of a shoe, shoe-supporting means, and means for moving said knives toward each other in directions generally transverse to the opposite edges of the sole adjacent to the heel-breast line to form shoulders in said sole 45 adapted to co-operate with a heel to be attached.
50. A sole-trimming machine comprising, in combination, a support for a shoe, a trimming knife, and means to move said knife inwardly adjacent to the heel-breast line 50 from the edge of the sole of the shoe about an axis generally parallel to the edge of the sole constructed and arranged to form adjacent to the heel-breast line a shoulder 55 adapted to co-operate with a heel to be attached to the shoe.
51. A sole-trimming machine having, in combination, means for supporting a shoe, and a pair of cutters moving inwardly from 60 opposite sides of the sole for trimming the rear end of the sole adjacent to the heel-breast line to provide shoulders adapted to co-operate with corresponding portions of a heel to be attached to the shoe.
52. A heel seat fitting machine for operating upon the sole of a shoe having, in combination, a cutter for forming a shoulder at the breast line of the sole, said cutter being disposed outside of the lateral edge of the sole and mounted for traversing movement 70 with respect to the sole, and guiding means for controlling said traversing movement in a manner to cause said shoulder on the sole to be curved in the plane of the sole.
53. In a sole trimming machine, in combination, a trimming cutter, and a pair of guides of different curvature constructed and arranged to be used alternatively to guide said trimming cutter transversely of a shoe sole at the heel breast line to make 80 alternative cuts of different curvature at the breast line of the sole to conform to the curvature of the breast of a given heel to be attached to said sole.
54. A heel seat fitting machine having, in combination, a knife arranged to make a breast cut in the sole of a shoe, means for causing any point in the edge of the knife to travel in a curved path as it makes the breast cut in the sole, and means for trimming surplus material from the periphery 90 of the heel seat of the sole.
55. A heel seat fitting machine having, in combination, a knife arranged to make a breast cut in the sole of a shoe, means for causing any point in the edge of the knife to move in a path curved about an axis substantially perpendicular to the sole of the shoe as the knife makes the breast cut, and means for trimming surplus material from 95 the periphery of the heel seat of the sole.
56. A heel seat fitting machine having, in combination, a knife arranged to make a breast cut in the sole of a shoe, and means for causing the knife to travel alternatively 100 in either a straight or a curved path as it makes the breast cut in the sole.
57. A heel seat fitting machine having, in combination, a knife arranged to make a breast cut in the sole of a shoe, and means for moving the knife laterally of the sole 110 and for swinging the knife about an axis substantially at right angles to the sole of the shoe to cause the cutting edge of the knife to move in a curved path as it makes 115 the breast cut.
58. A heel seat fitting machine, having, in combination, a pair of knives arranged to make breast cuts at the opposite edges of the sole of a shoe, means for moving the knives laterally of the sole, and means for swinging each knife about an axis substantially at right angles to the sole of the shoe 120 to cause the knives to move in correspondingly curved paths as they approach each other from opposite edges of the sole of the shoe.
59. A heel seat fitting machine having, in

combination, a knife formed with two intersecting cutting edges at an angle to one another, and means for causing the knife to travel laterally of the sole of a shoe operable to cause the knife to make a breast cut alternatively straight or curved as it passes into the sole of the shoe.

60. A heel seat fitting machine having, in combination, a cutter arranged to form a shoulder in the sole of a shoe adjacent to the heel breast line movably mounted for traversing movement with respect to the sole, and means for guiding said cutter in its traversing movement in a path curved about an axis forward of the heel breast line to cause the cutter to form a curved shoulder

corresponding to the curvature of the breast of the heel to be attached to the shoe.

61. A machine for trimming and beveling the periphery of the heel seat portion of a sole to prepare the sole for the reception of a wood heel having, in combination, a pair of clamping members formed and arranged to engage opposite surfaces of the central portion of the heel seat of the sole and to clamp and distort the heel seat portion of the sole, and cutting means arranged to bevel the distorted heel seat of the sole while it is thus clamped.

In testimony whereof I have signed my name to this specification.

CARL S. NORDEN.
